UNITED STATES PATENT OFFICE

WILLIAM COOK, OF NEW YORK, N. Y., ASSIGNOR TO WARMAN & COOK, INC.,
A CORPORATION OF NEW YORK

DESIGN FOR A LIGHTING FIXTURE

Application filed October 26, 1932. Serial No. 45,589. Term of patent 3½ years.

To all whom it may concern:

Be it known that I, WILLIAM COOK, a citizen of the United States of America, and a resident of New York, in the county of New York, and State of New York, have invented a new, original, and ornamental Design for Lighting Fixtures, of which the following is a specification.

The single figure of the drawings shows a perspective view of the lighting fixture, which is characterized by an opaque reflec-

tor in the upper portion and a large diffusing bowl below the reflector. The curved support rods such as are shown in the figure are three in number and spaced equally distant from each other, the third rod being concealed in the figure in the drawing behind the remainder of the fixture.

I claim:

The ornamental design for a lighting fixture as shown and described.

WILLIAM COOK.
